UNITED STATES PATENT OFFICE.

WALTER MINER, OF SEATTLE, WASHINGTON.

TRACK BRAKE.

Application filed April 16, 1927. Serial No. 184,392.

This invention relates to a track brake or car retarder for use in railway yards and at other places where it is desirable to retard movement of cars gravitating along the track.

One of the objects of the invention is to provide elongated gripping shoes having means actuated by the wheels of the car or cars for elevating them to active position.

10 A further object is to provide means for utilizing the weight of the car or cars for pressing the shoes against the faces of the wheels after said shoes have been brought to active positions.

15 A still further object is to provide means for locking the shoes in active positions during the movement of a car along the supporting rails.

A still further object is to provide means 20 controlled by the car for unlocking the shoes, thereby to permit them to shift automatically to inactive positions with the result that the retarding action of the shoes will be stopped.

25 With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 In the accompanying drawings, the preferred form of the invention has been shown.

In said drawings:

Figure 1 is a plan view of the brake 40 constituting the present invention.

Figure 2 is a side elevation of the structure shown in Figure 1.

Figure 3 is a section on the line 3-3, Figure 2.

45 Figure 4 is a section on the line 4-4, Figure 1.

Figure 5 is a section on the line 5-5, Figure 1.

Figure 6 is an enlarged section on the 50 line 6-6, Figure 2.

Figure 7 is a perspective view of the connecting block of the brake levers.

Figure 8 is a perspective view of one of the brake levers.

55 Figure 9 is an enlarged section through the switch control box.

Figure 10 is a section on line 10-10, Figure 9.

Figure 11 is a view showing, in diagram, a complete brake control mechanism.

Referring to the figures by characters of reference 1 designates parallel channel beams arranged in pairs and held properly assembled by attachment to ties 2. Secured between and to the channel beams 1 are up-standing guides 3. Each of these guides has an I-beam 4 mounted for yielding or sagging movement therein under the weight of a load, there being apertures 4' in the I-beam through which are extended transverse retaining bolts 5 connected to the guides. These bolts are preferably extended through spacing sleeves 6.

Extending along both sides of each rail, but normally spaced therefrom are elongated brake shoes 8 each of which is supported by a pair of levers 9. The lower end portions of the levers are fulcrumed within connecting blocks 10, each block being provided with two of these levers oppositely disposed, one lever being connected to each of the brake shoes. Short fingers 11 are extended toward each other from the lower ends of the levers and project under and are engaged by the I-beam 4. The guides 3 are provided with cross members 12 extending under the I-beams 4, these cross members being so located that when the I-beam is in its lowest position, it will rest on the cross members. When the connecting blocks 10 are in their normal positions they are so located below the I-beams 4 that the levers 9 will be supported along upwardly diverging lines as shown by broken lines in Figure 6.

Each block 10 is provided with depending flanges 13 pivotally connected to the upper end of a link 14 extending therebetween. The link is arranged between the channel beams 1 and has its lower end forked as at 100 15 so as to receive a roller 16 journaled in the link. This roller is adapted to bear upon the bottom of a run-way 17 provided between the beams 1 and formed preferably of a deep channeled member.

It is preferred to provide two pairs of levers 9 and one connecting block 10 adjacent each end of each pair of brake shoes, and each of the blocks 10 has one of the links 14 with its roller 16. It is desirable of course that these links 14 be shifted simultaneously for the purpose of operating the

brake. In order to effect this simultaneous actuation of the links the same are connected by strips 18 which can be adjustably connected at 19 by a turnbuckle or the like, said strips being mounted on the bearing pins 20 of the rollers 16 as shown especially in Figure 6. Interposed between and secured to the connecting strips is a cross member 21 having a stem 22 projecting therefrom and slidably within a guide lug 23. A spring 24 is mounted on this stem and bears at one end against the connecting member 21 and at its other end against the lug 23 so as thus to exert a constant thrust against the member 21 and cause the strips 18 to hold the rollers 16 normally thrust back from under the points of connection between the links 14 and the block 20. Thus the links will not support the blocks 10 in their highest position but, instead, will support them in the positions indicated by broken lines in Figure 6. The strips 18 are connected, at one end, by a cross rod 25 engaging the lower end of a crank arm 26. This crank arm extends downwardly from one end of a cross shaft 27 journaled on the channel beams 1 and extending transversely of but below the track rails. A head 28 is secured to one end portion of the shaft 27 so as to rotate, therewith, and hingedly connected to this head is a tripping lever 29 curved in the direction of its length and supported close to one side of the one of the track rails but beyond one end of the brake shoes. These relative positions of parts have been indicated clearly in Figures 1 and 2. As the tripping lever 29 is hingedly connected to the head 28, it can be swung laterally away from the rail whenever it is desired to render the mechanism inactive. In other words this tripping lever can readily be shifted into or out of the path of a car wheel travelling along the rail 7.

Extending inwardly from the inner channel beam 1 are brackets 30 on which are fulcrumed laterally extending levers 31. The outer ends of these levers are connected by links 32 to blocks 33 interposed between and secured to the strips 18. The inner ends of the levers are connected by links 34 to a rod 35 mounted within a guide 36 and arranged between the sides of the track. Pivotaly mounted on opposite sides of the rod 35 are latch levers 37 having beveled heads 38 for engagement with a tapered collar 39 carried by the rod 35. A spring 40 interposed between the latch levers serves to hold the heads 38 normally pressed toward each other. A toggle 41 connects the levers at one end to the core 42 of a solenoid 43. Under normal conditions the collar 39 is out of engagement with the heads 38 of the latch lever, the parts being positioned substantially as shown in Figure 1.

The blocks 10 are mounted for up and

down movement between the guide members 3 and additional guide members 44 secured between the channel beams 1, these guide members 3 and 44 serving to hold the blocks 10 against movement longitudinally of the beams 1 during the application of the brake. Furthermore the guide members 3 can be braced by means of crossed members 45 belted or otherwise connected thereto as shown in Figure 2.

Arranged at any suitable point within the railroad yard is a housing 46 in which is arranged an electric motor 47 the shaft 48 of which has a worm 59 adapted to drive a worm gear 50. This gear is secured to a shaft 51 having a small gear 52 rotatable therewith. A frame 53 is pivotally mounted within the housing and carries a segmental gear 54 provided with a cam 55. A stop 56 is carried by the cam and a spring 57, which is attached to the segmental gear and to the frame 53, serves to hold the stop normally pressed against the frame 53, as shown in Figure 10. A toggle 58 is connected to and interposed between the frame 53 and one wall of the housing 46, so as to hold the segmental gear 54 normally spaced from the small gear 52. This toggle is connected to the core 59 of a solenoid 60.

Mounted on the I-beams 4 adjacent one end of the brake shoe is a yieldingly supported strip 61 normally spaced from a contact spring 62 but adapted, when depressed, to move said contact spring against a fixed contact 63. These contacts are of course normally insulated from each other and from the strip 61 as shown in Figure 11. The two contacts 62 and 63 are electrically connected to the solenoid 60 so that when these contacts are brought together the solenoid will be energized and the toggle 58 actuated to draw the segmental gear 54 into mesh with the gear 52.

A rock shaft 64 is journaled in the housing 46 and has an arm 65 extending into the path of the cam 55. Another arm 66 is extended from the shaft 64 and engages a roller 67 carried by one end of a lever 68. This lever is electrically connected as at 69 to a battery 70 or other source of electricity and to the solenoid 43. In the path of lever 68 but normally spaced therefrom is a stationary contact 71 electrically connected, as at 72, to the solenoid 43.

Under normal conditions the parts are positioned as illustrated in Figures 1, 2 and 10. When the parts are to be operated the motor 47 is set in operation and this operation continues uninterrupted as long as desired. The motor therefore serves to drive the shaft 51 continuously but as the gears 52 and 54 are normally out of mesh, this rotation of the shaft will not produce any results under ordinary conditions. When a car approaches the track brake, the advanc-

ing wheels will pass between the outwardly diverging ends 73 of the shoes 8, but immediately prior to this, one of the wheels will move onto and depress the tripping lever 29. The depression of this lever will result in a pull being exerted through the crank arm 26 and the strips 18 upon the lower end portions of the links 14 with the result that these links will be swung away from the position shown for example in Figure 2 to an almost vertical position as shown in Figure 4. The blocks 10 will therefore be elevated from the broken line position shown in Figure 6 to the full line position and as the weight of the car is received by the rails 7 above the beams 4, said beams 4 will be thrust downwardly under the weight and depress the fingers 11. As a result of this action the brake shoes will be pressed firmly against opposed faces of the wheel passing therebetween with the result that the movement of the car will be retarded. When the trip lever 29 is depressed as explained, the strips 18 are pulled longitudinally. Motion will be transmitted through the links 32 and levers 31 to the links 34 and the rod 35 with the result that the tapered collar 39 on the rod 35 will be forced against and between the heads 38 with the result that these heads 30 and the latch levers 37 will snap into engagement with the collar 39 as shown in Figure 3, thereby holding the parts against retrograde movement. Immediately following the actuation of the parts as explained the rails 7 35 and the beams 4 supporting the same will be caused to sag slightly under the weight of the car passing therewith and this sagging action will be sufficient to cause the beams 4 to depress the fingers 11 and cause the levers 9 to swing toward each other. Consequently the brake shoes will be pressed tightly against opposed faces of the wheels of the car and the movement of the car will be greatly retarded.

45 As the single car being retarded approaches the far end of the brake mechanism one of the wheels W will depress the strip 61 and thereby close the circuit to the solenoid 60. This will result in the actuation of the toggle 58 so as to swing the frame 53 and move the segmental gear 54 into mesh with the gear 52. Consequently the segmental gear and its cam 55 will move away from their normal positions, the cam coming 50 against the arm 65 and causing the arm 66 to swing against the lever 68. Thus the circuit to the solenoid 43 will be closed by the contacts 71 and 68 with the result that the toggle 41 will be shifted to swing the latch levers 37 relative to each other and thereby to disengage the heads 38 from the collar 39. As the springs 24 have been held under compression by the latch levers 37 and the parts restrained thereby, these springs will 55 promptly shift the strips 18 and the links 14

when collar 39 is released with the result that the brake shoes 8 will swing outwardly from the car wheels due to the downward movement of the blocks 10 and consequently lowering of the fingers 11 relative to the beam 70 4. After the circuit has been broken between the contacts 62 and 63 by the passing of the car therefrom, the spring 57 which has been placed under tension when the magnet 60 was energized, will return the segmental gear 54 and the cam 55 to their normal positions, the toggle 58 dropping back to normal position to disengage gears 54 and 52. Of course this return movement of the parts will result in the breaking of the circuit to the solenoid 43 so that the lever 68 will swing away from the contact 71. It is intended to have the brake shoes of sufficient length to insure the proper slowing down of the car. This length will depend largely upon the speed at which the car is intended to approach the brake. It has been found in practice that a length of sixty feet is ordinarily required. The short strip 61 is located where it will be shifted by the car wheel as the car arrives at the remote ends of the brake shoes. As the shifting is momentary, the gear 54 will not have time to move out of mesh with gear 51.

The brake shoes can of course be provided with removable friction strips 74 which can be readily repaired or replaced, when worn.

Although the housing 46 has been shown provided with only one solenoid 60, it is to be understood that other solenoids and mechanisms cooperating therewith can be used in the housing these mechanisms being provided for different brakes or retraders located at different points in the railroad yards. In other words the electrical apparatus, other than the latch levers and their solenoids can all be located in a single housing located at some convenient point.

What is claimed is:

1. The combination with a track rail and a downwardly movable support therefor, of a track brake including elongated shoes at opposite sides of the rail, means operated by a car approaching the brake for shifting the shoes toward each other and for operatively connecting the shoes to the rail support, said support when depressed under the weight of a car thereon, being adapted to press the shoes toward each other when operatively connected to the rail support.

2. The combination with a track rail and a downwardly yieldable support therefor, of a track brake including elongated shoes at opposite sides of the rail, levers supporting the shoes, means operated by a car approaching a brake for shifting the levers against the rail support to move the shoes toward each other, said support when subjected to the weight of the car being adapted to impart further movement to the levers, thereby

press the shoes against opposite sides of a car wheel mounted on the rail.

3. The combination with a track rail and a yieldable support therefor, of a track brake including elongated shoes at opposite sides of the rail, levers supporting the shoes, means operated by a car approaching the shoes for lifting the levers thereby to press them against the rail-supporting means and 10 swing the shoes toward each other, means for automatically locking the levers and shoes in said position, said rail supporting means being adapted, when subjected to the weight of a car, to further actuate the levers 15 and press the shoes against the sides of a car wheel.

4. The combination with a track rail and yielding supporting means therefor, of a track brake including elongated shoes at 20 opposite sides of but above the rail, levers supporting the respective shoes, means operated by a car approaching the shoes for elevating the levers and the shoes, thereby to press the levers against the rail supporting 25 means and shift the shoes toward each other, means for automatically locking the levers and the shoes in shifted positions, said rail supporting means, when subjected to the weight of a car, being adapted to further 30 actuate the levers to press the shoes against the sides of the car wheels, and means controlled by a wheel of the car while passing between the shoes, for unlocking the shoes and levers.

5. The combination with spaced upstanding guides, a beam mounted therein to yield under the weight of a lead, and a track rail supported by the beam, of elongated brake shoes adjacent the sides of but above the rail, 40 movable means for supporting the shoes normally away from the rail, means actuated by a car approaching the shoes for shifting said movable means relative to the beam thereby to move the shoes toward the rail 45 therebetween, said movable supporting means and the beam cooperating to press the shoes against the sides of the wheels of a car on the rail when the beam is subjected to the weight of said car.

6. The combination with a track rail and a beam supporting the same adapted to yield when subjected to a load, of elongated brake shoes at opposite sides of but above the rail, means operated by a car approaching the 55 shoes for elevating the shoes relative to the rail and swinging said shoes toward each other, a latch for automatically fastening the shoes in elevated positions, said means and

the shoe shifting means cooperating to press the shoes against the sides of the wheel of 60 the car on the rail when the rail and the supporting beam are subjected to the weight of a car, and means operated by the car while moving relative to the shoes, for releasing the shoes.

7. The combination with a track rail and a beam supporting the same adapted to yield when subjected to a load, of elongated brake shoes at opposite sides of but above the rail, means operated by a car approaching the 70 shoes for elevating the shoes relative to the rail and swinging said shoes toward each other, a latch for automatically fastening the shoes in different positions, said means and the shoe shifting means cooperating to 75 press the shoes against the sides of the wheels of the car on the rail when the rail and the supporting beam are subjected to the weight of a car, and means operated by the car when moving relative to the shoes, for releasing the shoes, said means including a solenoid operatively connected to the fastening means, an electrically operated gear shift, and a circuit closer controlled by the gear shift electrically connected to the sole- 80 noid.

8. The combination with a track rail and a beam supporting the same adapted to yield when subjected to a load, of elongated brake shoes at opposite sides of but above the rail, 90 means operated by a car approaching the shoes for elevating the shoes relative to the rail and swinging said shoes toward each other, a latch for automatically fastening the shoes in different positions, said means and the shoe shifting means cooperating to 95 press the shoes against the sides of the wheels of the car on the rail when the rail and the supporting beam are subjected to the weight of a car, and means operated by the car when moving relative to the shoes for releasing the shoes, said means including a solenoid adapted, when energized, to actuate the fastening means to release the shoes, a switch for controlling a circuit to the solenoid, a 100 motor, a gear normally uncoupled therefrom, an electrically operated gear shift controlled by the last named car actuating means for coupling said gear to the motor, and means operated by the motor for actuating the switch and the solenoid.

In testimony that I claim the foregoing as my own, I have hereto affixed my signature.

WALTER MINER.
